DESIGN FOR A MOTION PICTURE PROJECTOR

George Kende, New York, N. Y., and Roland Salvatore, Lyndhurst, N. J., assignors to Universal Camera Corporation, New York, N. Y., a corporation of Delaware

Application December 16, 1939, Serial No. 88,938

Term of patent 7 years

To all whom it may concern:

Be it known that George Kende and Roland Salvatore, both citizens of the United States and residents, respectively, of the city, county, and State of New York, and of Lyndhurst in the county of Bergen and State of New Jersey, have invented a new, original, and ornamental Design for a Motion Picture Projector, of which the following is a specification, reference being had to the accompanying drawing forming part thereof, in which,

Fig. 1 is a perspective view of a motion picture

projector embodying our design and showing the side and front thereof;

Fig. 2 is a side elevational view thereof showing the opposite side to that shown in Fig. 1; and

Fig. 3 is a rear elevational view thereof.

We claim:

The ornamental design for a motion picture projector, substantially as shown.

GEORGE KENDE.
